US00D621215S

(12) **United States Design Patent**
Bruno et al.

(10) **Patent No.:** **US D621,215 S**
(45) **Date of Patent:** **** Aug. 10, 2010**

(54) **GRILL FRAME STRUCTURE**

(75) Inventors: **Adrian A. Bruno**, Rolling Meadows, IL (US); **Charles Choi**, Chicago, IL (US); **Sonny Siazon**, Woodstock, IL (US)

(73) Assignee: **Weber-Stephen Products Co.**, Palatine, IL (US)

(**) Term: **14 Years**

(21) Appl. No.: **29/346,759**

(22) Filed: **Nov. 5, 2009**

Related U.S. Application Data

(63) Continuation-in-part of application No. 29/344,963, filed on Oct. 7, 2009.

(51) **LOC (9) Cl.** **07-02**

(52) **U.S. Cl.** **D7/403**

(58) **Field of Classification Search** **D7/332, D7/334–337, 402–405; 99/339, 449, 450, 99/482; 126/25 R, 9 R, 41 R, 50, 276, 304 A, 126/268; D6/511, 574; 211/90.01; 248/129, 248/150–151**

See application file for complete search history.

(57) **CLAIM**

The ornamental design for a grill frame structure, as shown and described.

DESCRIPTION

FIG. 1 is a perspective view of a grill frame structure embodying the invention;

FIG. 2 is a second perspective view thereof;

FIG. 3 is a front view thereof;

FIG. 4 is a top view thereof;

FIG. 5 is right side view thereof;

FIG. 6 is a left side thereof;

FIG. 7 is a bottom view thereof; and,

FIG. 8 is a rear view thereof.

The details shown in broken lines form no part of the claimed design.
